UNITED STATES PATENT OFFICE

2,137,870

HEATING APPARATUS

James C. Woodson, Cleveland, Ohio, assignor to
 Lee Wilson Sales Corporation, a corporation of
 Ohio

Application December 30, 1937, Serial No. 182,504

1 Claim. (Cl. 263—42)

This invention relates to heating apparatus and, in particular, to a heat exchange tube for a furnace such as that disclosed in Wilson Patent No. 1,952,402.

5 Heat exchange tubes for installation in furnaces of the type shown in said patent have heretofore been cast from alloy steel which remains rigid at elevated temperatures. These castings are relatively costly and it is an object of the present invention to provide heat exchange tubes which are less expensive to manufacture, which are equally as efficient as the cast tubes, if not more so, from the standpoint of heat transmission, and have other important advantages. In accordance 10 with my invention I provide a heat exchange tube, the straight portion of which is fabricated from flat stock by bending it to cylindrical form and welding the abutting edges. One or more cast elbows associated with the fabricated portion 15 completes the tube. The elbows preferably have a thicker wall section than the straight portion of the tube to resist the abrasive effect of the combustion gases and the elbows are also swelled out between their ends. An assembly of such elbow 20 or elbows and a fabricated straight tube provides a composite heat exchange tube in which relative movement of the parts is permitted on expansion and contraction thereof, thus entirely avoiding the stresses set up in an integral tube on heating 25 and cooling thereof.

A complete understanding of the invention may be obtained from the following detailed description thereof referring to the accompanying drawings illustrating a preferred embodiment with 30 certain modifications. In the drawings:

Figure 1 is a partial transverse section through a furnace of the same general type as shown in the aforementioned patent, with the invention incorporated therein;

40 Figure 2 is a partial longitudinal sectional view of the furnace;

Figure 3 is a view partly in section and partly in elevation showing the construction of my composite tube in detail;

45 Figure 4 is an elevation of the lower elbow of Figure 3;

Figure 5 is a plan view thereof; and

Figure 6 is a partial sectional view showing a modified form of upper elbow.

50 Referring now in detail to the drawings, the furnace indicated generally at 10 comprises a heating cover 11 removably disposed on a base 12. The base comprises a hearth 13 supported on a structural framework indicated generally at 14 having piers 15 built up thereon for supporting

charges of material to be treated such as stacks of sheets 16. Protective covers 17 are disposed over the stacks with their lower edges seated in sealing channels 18.

The heating cover comprises a refractory lining 19 in a structural frame 20. Heat exchange tubes 21 have vertical portions 22 and horizontal portions 23 and 24, the latter extending through openings in the side walls of the cover 11. The heat exchange tubes are spaced along the side 10 walls and may also be installed on the end walls of the heating cover. The horizontal portions 23 and 24 have elbows 25 and 26 formed integral therewith. A stack portion 27 extends upwardly from the horizontal portion 23. A refractory 15 lined passage 28 encloses the lower ends of the stack portions 27 and the outer ends of the horizontal portions 23. Seals 29 are provided at the upper ends of the stack portions 27, a sealing channel 30 being formed on top of the passage 28. 20

Burners 31 extend into the horizontal tube portions 24 and are connected to a fuel supply main 32 carried on brackets 33 secured to the framework of the cover 11.

Referring now more particularly to Figures 3 25 through 6 for a detailed showing of the tubes 21, it will be seen that the fabricated portions 22 thereof have a thinner wall section than the cast portions 23 and 24. It will also be observed that the latter are provided with reduced ends 34 which 30 cooperate with the lower and upper ends of the portion 22 to form bell and spigot joints. These joints may be made permanent by welding as at 35 if desired. Expansion and contraction of the resulting unitary tube is permitted by the clearance between the portion 23 thereof and the side 35 wall of the furnace as shown in Figure 1. It will also be observed that the elbows 25 and 26 are somewhat larger in cross-sectional area than the horizontal sections 23 and 24. This permits combustion gases from the burners 31 to sweep around the elbows with a minimum of abrasion or scouring of the latter.

A modified form of upper elbow is shown in Figure 6 at 36. Like the tube portions 23 and 24, 45 this is a casting adapted to cooperate with a vertical tube portion 27. The tube portion 36 is similar to that shown at 23 except that it does not have the stack portion 27.

The principle of the invention may also be applied to heat exchange tubes of slightly different construction, as shown in Figure 2. These tubes are usually employed between adjacent stacks of sheets and may extend inwardly from the side or end walls of the cover 11. They include an 50 55

elongated horizontal portion 38 having an elbow 39 and a vertical portion 40 extending upwardly through the roof of the cover and having seals 41 at the upper ends thereof. Hangers 42 depending from the roof of the cover provide support for the inner ends of the tubes. The outer ends are fixed in the wall of the cover, in the same manner as the horizontal tube portions 24. Burners 43 are mounted in the vertical tube portions 38 and are supplied with fuel from a main 44.

The vertical portions 40 of the tubes shown in Figure 2 are preferably fabricated by forming and welding flat stock, in the manner already described with reference to the vertical tube portions 22. The elbows 39 are similar to those shown at 26 while the horizontal tube portions 38 are similar to the tube portions 24 except that they are longer. Alternatively, the horizontal portions 38 may also be fabricated from flat stock 20 and connected to the elbows 39 by bell and spigot joints such as illustrated in Figure 3. The vertical tube portions 40 have tabs 45 welded thereto with slots 46 therein. These slotted tabs engage studs 47 welded to the elbows 39, thus providing a relatively loose connection between the vertical and horizontal tube portions. This permits expansion and contraction of the tube portions 38 and 40 without introducing undesirable stresses into these parts. The hangers 42 include rollers 48 which facilitate expansion and contraction of the horizontal tube portion 38.

The thickness of the wall of the vertical tube portions 40 is less than that of the elbows 39, the ratio of thicknesses being about as shown in Figure 3. The same is true of the horizontal tube portions 38 if they are fabricated instead of cast integral with the elbows 39.

It will be apparent from the foregoing explanation that the heat exchange tube disclosed possesses marked advantages over similar tubes as heretofore constructed, from the standpoint of manufacturing cost, thermal efficiency and useful life. The portions of the tube subject to the greatest wear, viz., the elbows where the di-

rection of the combustion gases is changed, are composed of castings having a wall thickness sufficient to stand the abrasive or scouring action of the gases for long periods of time. The vertical portions of the tubes, being fabricated from flat stock somewhat thinner than the walls of the cast elbows, have ample strength and, at the same time, are more efficient from the standpoint of heat transfer than tubes cast in one piece with substantially the same wall thickness throughout. The vertical portions of the tubes, obviously, are subjected to relatively little scouring action by the gases passing therethrough. The advantage of the composite tube shown in Figure 2 in avoiding stresses due to expansion and contraction has already been mentioned as has also the fact that provision is made for free expansion and contraction of the tubes of the type shown in Figure 1, the parts of which are permanently attached by welded joints. Even without this special provision, the flexibility of the vertical tube portions 22 resulting from their relatively thin wall section permits them to compensate for considerable expansion and contraction without stressing the cast portions 23 and 24 to a serious degree.

Although I have illustrated and described herein but a preferred embodiment of the invention with certain modifications, it will be understood that changes in the construction disclosed may be made without departing from the spirit of the invention or the scope of the appended claim.

I claim:

A radiant heating element adapted to be mounted within an enclosure to be heated, such as a furnace, said element comprising a substantially cylindrical tube for conveying hot fluids and an elbow communicating with one end of said tube, said elbow having one end of substantially the same size as said tube and an intermediate portion swelled out to provide a sectional area substantially greater than that of said tube.

JAMES C. WOODSON.
